UNITED STATES PATENT OFFICE.

ROBERT A. KOHLHEPP, OF WALLINGFORD, CONNECTICUT, ASSIGNOR TO
LANDERS, FRARY AND CLARK, OF NEW BRITAIN, CONNECTICUT.

DESIGN FOR A FERRULE.

SPECIFICATION forming part of Design No. 35,819, dated March 18, 1902.

Application filed February 19, 1902. Serial No. 94,842. Term of patent 7 years.

To all whom it may concern:

Be it known that I, ROBERT A. KOHLHEPP, a citizen of the United States, residing at Wallingford, in the county of New Haven and State of Connecticut, have invented and produced a new and original Design for a Ferrule, of which the following is a specification, reference being had to the accompanying drawings, forming part thereof.

Figure 1 is a side elevation of a ferrule for cutlery, showing my new design. Fig. 2 is a plan view of the same.

As shown in the drawings, the handle end of the oval ferrule is provided with a plain band 3 and bead 4, while the bolster end has the quarter-bead 5. The body of the ferrule 6, between the said beads 4 and 5, is mainly

plain with a swelling middle portion. At the top and bottom there is a projecting middle band or rib 7, with a lesser rib 8 on each side. At each end of the body 6 there are leaflets 9, resting on the beads 4 and 5 as a base and extending toward each other on the plain body, as shown.

Having described my invention, what I claim as new, and desire to secure by Letters Patent, is—

The design for a ferrule, as herein shown and described.

ROBERT A. KOHLHEPP.
